UNITED STATES PATENT OFFICE.

WILLIAM WALLACE HANSCOM, OF SAN FRANCISCO, CALIFORNIA, ASSIGNOR TO
NATIONAL RADIO COMPANY, OF SAN FRANCISCO, CALIFORNIA, A CORPORA-
TION OF ARIZONA.

MULTIUNIT TELEPHONE-TRANSMITTER.

1,264,507.

Specification of Letters Patent. Patented Apr. 30, 1918.

Application filed February 27, 1917. Serial No. 151,185.

To all whom it may concern:

Be it known that I, WILLIAM W. HANS-
com, a citizen of the United States, residing
at the city and county of San Francisco and
5 State of California, have invented new and
useful Improvements in Multiunit Tele-
phone-Transmitters, of which the follow-
ing is a specification.

This invention relates to a heavy current
10 multi-unit telephone transmitter particu-
larly adapted for wireless telephony, long
distance service and the like.

One of the objects of the present invention
15 is to provide a novel mounting for the
carbon cells in the transmitter and in con-
junction therewith a common cooling cham-
ber for the same. Another object of the in-
vention is to provide a diaphragm prefer-
20 ably constructed of foraminated material
and to provide means for freely supporting
the cooling chamber and the cells to prevent
distortion not only of the main diaphragm
but also of the auxiliary cell diaphragm.
Further objects will hereinafter appear.

25 The invention consists of the parts and the
construction and combination of parts as
hereinafter more fully described and
claimed, having reference to the accom-
panying drawings, in which—

30 Figure 1 is a central vertical longitudinal
section through the telephone transmitter;

Fig. 2 is a detail side elevation showing the
circuit connection between two carbon cells;

Fig. 3 is a cross section partly broken
35 away taken on the line 3—3 of Fig. 1;

Fig. 4 is a front view of the transmitter
showing the mouth-piece removed.

Referring to the drawings in detail, A
40 indicates the main casing of the transmitter,
2 the mouth-piece, 3 the main diaphragm, 4
the carbon cells, and 5 the cooling cylinder.
The cooling chamber is in this instance cy-
lindrical in shape and so shallow as to give
45 it a disk-like appearance. It consists of an
annular wall 6, a front plate 7 and a rear
plate 8 which are secured together in any
suitable manner. A chamber 9 is thereby
formed between the front and rear plates
50 for the reception of a cooling fluid which is
circulated therethrough in a manner here-
inafter to be described. Extending through
the front and rear plates of the cylinder
5 is a plurality of tubes 10 and extending
through the rear plate is a pair of tubes 11

and 12. The inner ends of these tubes are 55
closed and the tube 11 is provided with a
discharge opening 13 positioned in the di-
rection indicated, while the tube 12 is pro-
vided with an intake opening 14 facing in
the opposite direction. 60

A cooling medium, such as water, enter-
ing through pipe 11 will therefore discharge
through the opening 13 in the direction of
the arrow shown and will therefore circu-
late around the tubes 10 and finally dis-
charge through the intake 14 and the
tube 12. 65

Six carbon chambers are employed in the
present instance and each is provided with
an extension stud 15, the outer end of which 70
is threaded for the reception of a pair of
lock nuts. Each stud is inserted through a
tube 10 and the nuts when applied will
therefore rigidly secure the carbon cham-
bers against the front plate 7. All metal 75
portions of the carbon chambers are insu-
lated from the cooling cylinder by means of
thin mica tubes and washers and the elec-
tric circuit is completed through the carbon
chambers in series or series multiple as may 80
be desired by means of thin copper strips
16 clamped under the nuts at the back of
the cooling cylinder or under the transmitter
diaphragm.

The circuit passing through the carbon 85
cells is first connected with the stud of the
cell shown at 17. A thin copper strip 18
secured between the cell and the main dia-
phragm connects the cell 17 with the cell
18^a or the second cell. A second strip 19 90
secured between the washers on the rear
side of the cylinder forms a circuit be-
tween cells 18^a and 20. A third strip 20^a
positioned between the main diaphragm and
the cylinder forms a circuit between the 95
cells 20 and 21 and a fourth strip 23 se-
cured between the washers on the rear side
of the cooling chamber forms a circuit be-
tween cells 21 and 24 while a fifth strip 25
forms a circuit between cells 24 and 26. 100
Each connecting strip is alternately posi-
tioned one on each side of the cooling cylin-
der and thereby forms a series circuit
through the cells.

The front side of each carbon cell is also 105
provided with a stud and each of said studs
are secured by means of nuts and washers to
the main diaphragm 3. This diaphragm

may be constructed of mica, but if metal is employed it is obvious that insulating washers must necessarily be interposed.

It is understood that the carbon cells are entirely insulated from one another and the metal diaphragm and that any connections between them and the outgoing terminals are made by means of the thin copper strips before-mentioned. The diaphragm may be of any suitable size and any suitable material and mounted in the transmitter casing by any improved means. I, however, show and prefer that its outer edge be surrounded by a rubber tubing or similar soft cushioning material to permit it to be clamped between the front face of the transmitter casing and the inner face of the mouth-piece which screws thereon. The present diaphragm is perforated by six circular slots such as shown at 27 leaving a small connecting bridge 28 between each perforation. The bridges are, however, of sufficient width to form a strong connection between the inner and outer portions on the diaphragm without interfering with the vibrations of the inner portion to any appreciable extent. The reason for perforating the diaphragm or leaving the bridges, such as shown, is to permit of a comparatively free motion of the central portion so that it can respond readily to the sound vibrations impinging against it and thereby have the maximum effect upon the carbon granules in the cells.

Extending through the center portion of the cooling cylinder is a tube 30 and secured to the inner face of the main casing A is a stud 31. This stud extends through the tube 30 and as the tube is slightly larger in diameter a sliding fit is permitted which prevents any binding action between the supporting stud and the cooling cylinder supporting the carbon cells. This is an important feature as it leaves the cooling cylinder free on the stud to find its own position and therefore does away with the necessity of the very careful adjustment necessary when the cooling chamber or back supports for the carbon cells are rigidly secured to the casing, for the reason that it is very essential to have the main and auxiliary diaphragms of the cells free to prevent distortion of the same when operating or at rest.

If both the main diaphragm and cooling cylinder are rigidly secured in place, it can readily be seen that each will have to be adjusted with reference to the other, as any tightening of the main diaphragm by screwing the mouth-piece against the rubber tubing will affect the adjustment of the diaphragm with reference to the carbon cells and the cooling chamber, this being due to the fact that the main diaphragm is surrounded by a rubber ring which is compressible and will allow the edge of the diaphragm to be moved through a certain dis-

tance by varying the pressure on the ring or gasket.

The transmitter constructed as shown may be assembled at the factory and all the working parts as a unit may be placed in the casing by unscrewing or removing the front mouth-piece. The parts when inserted are clamped and secured in position ready for service as soon as connection to the operating circuit and water supply is made and there are no adjustments or tools required to make these connections. In other words, after assembly at the factory the transmitter proper is adjusted once and for all and ready to be set in the casing without further attention.

By having one large main chamber for cooling all the carbon cells instead of a separate cooling chamber for each, I simplify and cheapen the construction, besides making a substantial base to which all other parts are secured and adjusted permanently.

The present transmitter is more or less of the inertia type in that the inertia of the cooling cylinder and its attachments is such as to prevent it from following the rapid impulses given the diaphragm by sound waves, this permits it to adjust itself automatically to the position of least distortion.

I wish it understood that various changes in the materials and finish and minor details of construction may be resorted to within the scope of the appended claims, and that I do not wish to limit myself to the specific design and construction here shown.

Having thus described my invention, what I claim and desire to secure by Letters Patent is:—

1. In a multi-unit telephone transmitter a casing, a diaphragm, a cooling cylinder mounted within the casing, a plurality of carbon cells secured on one side of the cooling cylinder and on the opposite side to the diaphragm, and means for circulating a cooling medium through the cylinder.

2. In a multi-unit telephone transmitter, a casing, a diaphragm, a cooling cylinder slidably mounted within the casing, a plurality of carbon cells secured on one side of the cooling cylinder and on the opposite side to the diaphragm, and means for circulating a cooling medium through the cylinder.

3. A telephone transmitter comprising in combination a casing, a diaphragm, a series of resistance cells each of which is rigidly connected at one end to the diaphragm and has a terminal projecting outwardly from its opposite end, a common cooling cylinder in which said terminal ends are secured, and means for circulating a cooling liquid around said terminal ends and through the cylinder.

4. A telephone transmitter comprising in combination a casing, a diaphragm, a series of resistance cells each of which is rigidly

connected at one end to the diaphragm and has a terminal projecting outwardly from its opposite end, a common cooling cylinder in which said terminal ends are secured, a stud 5 secured in the casing in which said cylinder is slidably mounted and means for circulating a cooling liquid around said terminal ends and through the cylinder.

5. In combination with the diaphragm of 10 a telephone transmitter of a series of resistance cells secured to the diaphragm, a terminal projection on each cell, a common cooling cylinder through which said terminal members pass and to which they are rigidly secured, and means for insulating the 15 cells and terminal members with relation to the cooling cylinder and diaphragm.

6. In combination with the diaphragm of

a telephone transmitter of a series of resistance cells secured to the diaphragm, a terminal projection on each cell, a common cooling cylinder through which said terminal members pass and to which they are rigidly secured, means for insulating the cells and terminal members with relation to the cooling 20 cylinder and diaphragm, and a supporting member upon which the cylinder is slidably mounted.

In testimony whereof I have hereunto set my hand in the presence of two subscribing 25 witnesses.

WILLIAM WALLACE HANSCOM.
